UNITED STATES PATENT OFFICE.

WILLIAM M. ASH, JR., OF ALTON, ILLINOIS.

HEADLIGHT LAMP.

Application filed May 4, 1925. Serial No. 27,934.

To all whom it may concern:

Be it known that I, WILLIAM M. ASH, Jr., a citizen of the United States, residing at Alton, in the county of Madison and State of Illinois, have invented new and useful Improvements in Headlight Lamps, of which the following is a specification.

In the headlamps for automobiles and the like, the rays of light are directed from the lamp bulb to all parts of the conical reflector. The result is that these light rays are frequently directed into the eyes of the driver of an approaching automobile so that he is liable to lose control of his machine and both machines are liable to accident. The object of this invention is the provision of an extremely suitable and cheaply constructed means for directing rays of light from a bulb in a headlamp upwardly toward the top of the reflector so that such rays are from thence deflected downwardly, and whereby the road ahead of the machine will be amply illuminated and the rays of light will be prevented from reflecting into the eyes of the drivers of approaching machines.

The drawings which accompany and form part of this application illustrate a satisfactory embodiment of my improvement, and wherein:

30 Figure 1 is a perspective view of a shield in accordance with this invention.

Figure 2 is a similar view but showing one of the back portions of the shield disassociated from the other.

35 Figure 3 is a side elevation with the lamp bulb arranged in the shield.

Figure 4 is a front elevation thereof.

Figure 5 is a front elevation of a headlamp showing the shield positioned therein.

40 My improved deflector shield is formed from a single strip of suitable lustrous metal. The strip or sheet is of a substantially rectangular shape, and is centrally bent upon itself to provide the sides 1 and 2 of the reflector.

45 The outer edges of the sides 1 and 2 are beaded, as at A. In a line with the juncture of the sides 1 and 2 the metal strip is slit from one of its ends and the projecting portions of the said strip are then bent inwardly and rightangularly with respect to the sides 1 and 2. These portions are arranged inlapping relation and provide the back of the shield. The inner section 4 of the back has its outer edge formed with an extension 5. The outer section 6 has its outer edge formed with a similar extension 7.

When the sections 4 and 6 are arranged against each other, the extension 5 is bent over the section 6, and the extension 7 is bent inwardly over the section 4. In this manner 60 the back of the shield is two-fold and the sections constituting the same are connected without the employment of solder, rivets or analogous means. Thus it will be noted that the shield can be easily and cheaply 65 constructed.

The back of the shield is provided with a central rounded opening 8 and the wall provided by this opening is notched, as at 9. This notch is of sufficient depth to permit of the sustaining lugs 10 on the metal base 11 of a lamp bulb 12 passing therethrough. The base 11 has arranged therearound a coil spring 13 that is designed to contact with the socket in the headlamp 14. 70 In this manner it will be noted that the shield is effectively sustained on the lamp bulb. The shield is placed below the lower portion of the lamp bulb 12 but may be arranged at a slight angle thereto, as shown 75 in Figure 5 of the drawings. As the shield is of a size to fully enclose the lamp bulb, the rays of light from the lower portion thereof will not be directed against the conical reflector 15 in the headlamp but will be directed against the upper portion of the said reflector. These rays will be then deflected 80 downwardly, and while the lamps illuminate the roadway directly ahead of the machine the rays therefrom will not reach 85 the eyes of the drivers of approaching machines, so that accidents which frequently occur from this cause will be effectively obviated.

The metal could be lustrous or painted 90 a dull gray, or metal of dull non-reflective properties, so as to prevent reflection from the shield about light bulb; also the improvement might be constructed of suitable 95 card-board.

Having described the invention, I claim:

1. A shield for the purpose set forth constructed from a single sheet metal which is centrally bent upon itself to provide rightangular sides, said member being slit from one of its ends in line with the juncture of the sides and the metal in the terminal of the slit being bent in opposite directions on the respective sides to provide a two-ply 105 back for the shield.

2. A shield for the purpose set forth con-

structed from a single sheet metal which is centrally bent upon itself to provide right-
angular sides, said member being slit from
one of its ends in line with the juncture of
5 the sides and the metal in the terminal of
the slit being bent in opposite directions on
the respective sides to provide a two-ply
back for the shield, the elements constituting

the back having extensions designed to be
bent over the respective sections and said
back having a rounded opening there-
through and a notch communicating with
the said opening. 10

In testimony whereof I affix my signature.

WILLIAM M. ASH, JR.
